(57) **CLAIM**

The ornamental design for a steering wheel, as shown and
described.

DESCRIPTION

FIG. 1 is a front view of the inventive steering wheel;

FIG. 2 is top view of the inventive steering wheel;

FIG. 3 is a right side view of the inventive steering wheel;

FIG. 4 is a bottom view of the inventive steering wheel;

FIG. 5 is a left side view of the inventive steering wheel;

FIG. 6 is a rear view of the inventive steering wheel;

FIG. 7 is an alternative front view of the central portion of the
inventive steering wheel removed from the outer portion.

The broken lines represent portions of the structure that form
no part of the claim.

1 Claim, 6 Drawing Sheets
